UMBRELLA FERRULE

Joseph Levin, Lancaster, Pa., assignor to Polan, Katz & Company, Baltimore, Md.

Application May 8, 1943, Serial No. 486,211

7 Claims. (Cl. 135—34)

This invention relates to umbrella ferrules and removable covers.

At the present time the construction of an umbrella includes a frame which is formed of a stick, collapsible ribs, a flexible cover, and a ferrule for holding the cover on the stick. The trend of the umbrella manufacturers is to provide a removable cover which includes the flexible cover body, tips stitched to the outer margin of the cover body and a ferrule secured to the center of the cover body.

An object of this invention is to provide a removable cover which incorporates an improved ferrule formed of two parts which are locked together, the ferrule parts when in locked position also clamping the reinforced center of the cover therebetween.

Another object of this invention is to provide a two-part ferrule which includes a cap-shaped body for mounting on the outer end of the stick, the body being formed with an inner flange and a pair of locking lugs outwardly of the flange, and which also includes a clamping ring adapted to be snapped over the locking lugs, the ring being sufficiently large in its diameter to admit distortion thereof in order to slip the ring over the clamping lugs, and being sufficiently flexible so that it may be easily distorted to pass over the locking lugs.

Embodying the above objects and others which may hereinafter appear, the invention consists of the novel construction, combination and arrangement of parts, as will be more specifically referred to and illustrated in the accompanying drawing wherein is shown an embodiment of the invention, but it is to be understood that changes, modifications and variations may be resorted to which fall within the scope of the invention as claimed.

In the drawing:

Figure 1 is a sectional view partly broken away of an umbrella assembly embodying this invention.

Figure 2 is an exploded view of the assembly, and

Figure 3 is a fragmentary plan view of the center of the cover.

Referring to the drawing, the numeral 10 designates generally an umbrella frame which includes a stick 11 having secured to the outer end portion thereof a slotted ring 12 including a sleeve 13. A plurality of ribs 14 are adapted to be secured in the slots of the ring 12 by means of a wire 15.

A flexible cover generally designated as 16 is

adapted to removably engage over the frame 10 and includes a cover body 17 which has secured to the outer margin thereof a plurality of tips 18 which are secured to the cover body 17 by stitching 19. The outer ends of the ribs 14 are formed with reduced end portions 20 which are adapted to engage in the sockets 21 formed in the tips 18. The cover body 17 is adapted to be reinforced at the center thereof, the center being formed with a hole or opening 22 and stitches 23 are then overcast about the edge of the opening 22. A disc-shaped member 24 is also adapted to be tacked to the inner side of the cover 17 by widely spaced stitches 25.

The disc-shaped member 24 is formed with a central opening 26 adapted to register with the opening 22. A puff 27 is adapted to be stitched to the outer side of the cover body 17 by means of stitches 28. The puff 27 is formed with a central opening 29 adapted to register with the openings 22 and 26.

A ferrule structure generally designated as 30 is adapted to be secured to the center of the cover body 17 and is adapted to telescope over the outer projecting end of the stick 11. The ferrule structure 30 includes a hollow body 31 formed with a socket 32 within which the stick 11 is adapted to tightly engage. The body 31 is also formed with an opening 33 at the inner end of the socket 32 which is of larger diameter than the socket 32 for receiving the sleeve 13 of the slotted ring 12. The body 31 at the inner end thereof is formed with an annular flange 34 against which the disc-shaped member 24 is adapted to engage.

The cover body 17 is tightly clamped on the flange 34 by means of an annular clamping ring 35. The clamping ring 35 has an inner diameter slightly greater than the outer diameter of the body 31 so that the clamping ring 35 may readily be distorted and passed over a pair of diametrically opposed clamping lugs 36 which are formed on the body 31 outwardly from the flange 34. The inner edge of the clamping ring 35 is adapted to bear against the puff 27, as shown in Figure 1, so as to tightly clamp the center of the cover 17 against the flange 34.

The provision of the two-part ferrule structure hereinbefore described permits the complete assembly of the cover body 17 with the disc-shaped member 24 and the puff 27 prior to securing of this structure on the ferrule. After the cover assembly has been formed by the stitchings 23, 25 and 28, the ferrule body 31 may be slipped through the aligned openings of the cover body

11, the disc 24 and the puff 27. The cover structure is passed over the clamping or locking lugs 36 and the clamping ring 35 may then be slipped over the body 31, being distorted as it passes over the clamping or locking lugs 36 until the outer edge of the clamping ring 35 bears against the inner ends of the locking lugs 36. At this time the ring 35 will assume its normal annular configuration and the ring 35 will also bear tightly against the puff 27.

By providing an umbrella structure including a removable cover as hereinbefore described, it is possible to replace the cover assembly 16 with the tips 18 secured to the outer margin thereof and the user of the umbrella may remove the clamping ring from the ferrule and remove the old or worn cover. The new cover assembly may then be slipped over the ferrule body 31 and the clamping ring replaced. Of course, if desired the cover assembly may also include the ferrule structure 30 so that the user may align the tips 18 to the outer ends of the ribs and slip the ferrule body 31 over the outer end of the stick 11.

It will be understood that the stick 11 may be either frictionally held in the socket 32 or may be glued or otherwise firmly secured therein. The ferrule structure 30 may be made out of any suitable material and may be readily made out of plastic or the like.

What I claim is:

1. An umbrella having a frame including a stick, and a cover assembly mounted on said frame, said assembly comprising a flexible cover member, and a ferrule structure secured to the center of said cover member, said ferrule structure including a flanged socket member engageable over the outer end of said stick, a distortable cover clamping ring about said socket member, and locking means carried by said socket member for said clamping ring, said ring adapted to be forced over said locking means to be thereby held in cover clamping position.

2. An umbrella having a frame including a stick, and a cover assembly, said assembly comprising a flexible cover member, and a ferrule structure secured to the center of said cover member, said ferrule structure including a

flanged socket member engageable over the outer end of said stick, a clamping ring loosely engageable about said socket member, and locking means for said ring fixed to said socket member.

3. In a cover assembly for an umbrella frame of the type comprising a flexible cover, a ferrule structure secured to the center of said cover, a ferrule structure comprising a socket member, a flange carried by said member, a clamping ring loosely engaging about said member for clamping said cover on said flange, and a pair of locking lugs carried by said member outwardly of said flange for locking said ring in clamping position.

4. An umbrella ferrule comprising a body formed with a socket for receiving the stick, a flange on the inner end of said body, a cover clamping ring loosely engaging about said body for clamping the cover on said flange, and a pair of ring locking lugs carried by said body outwardly of said flange for locking said ring in clamping position.

5. An umbrella ferrule comprising a body formed with a socket for receiving the stick, a flange on the inner end of said body, a resilient cover clamping ring loosely engaging about said body for clamping the cover on said flange, and a pair of ring locking lugs carried by said body outwardly of said flange for locking said ring in clamping position, said lugs projecting from said body and wherever said ring is temporarily distorted and forcibly passed when said ring is moved to clamping position.

6. An umbrella ferrule comprising a ferrule body, a cover clamping ring, and means carried by said body for holding said ring in clamping position.

7. An umbrella ferrule comprising a pair of cover clamping members, and means securing said members together, said means being carried solely by one of said members and comprising a lug element, one of said members comprising a resilient ring and the other of said members comprising a body formed with a socket for receiving the stick of an umbrella.

JOSEPH LEVIN.
